To all whom it may concern:

Be it known that I, ANDREW LITTLE, of the city, county, and State of New York, have invented and produced a new and original Design for a Font of Printing-Type, of which the following is a specification.

as shown, upon the right, and in the case of the T and Z upon the right and left.

The character of the design is preserved in the dollar-mark, the figures, and in the punctuation-marks.
